LESTER DAY, OF BUFFALO, NEW YORK, ASSIGNOR TO HIMSELF
HENRY F. BRIGGS, AND EDWARD BELDING, OF SAME PLACE.

Letters Patent No. 83,475, dated October 27, 1868.

IMPROVEMENT IN APPARATUS FOR TRANSPORTING, EXTENDING, AND ELEVATING
PIPES AND HOSE.

The Schedule referred to in these Letters Patent and making part of the same.

To all whom it may concern:

Be it known that I, LESTER DAY, assignor to myself, HENRY F. BRIGGS, and EDWARD BELDING, all of Buffalo, in the county of Erie, and State of New York, have invented certain new and useful Improvements in Extension-Pipes and Hose-Elevators; and I do hereby declare that the following is full and exact description thereof, reference being had to the accompanying drawings, making part of this specification.

The object of my invention is to provide a fire-machine that will throw water to a great height, and it consists in attaching to a suitable carriage or platform an extension-pipe, which, as it is extended, carries up hose with it; also, in providing suitable attached apparatus for working the same; and, furthermore, in connecting with the carriage a reservoir to be filled with water when the pipe is being used, to steady the whole machine.

Figure 1 is a perspective view of the whole machine, the red line showing the pipe elevated for use.

Figure 2 is a longitudinal section of the pipe and case, also showing the hose-connection, and belt for raising it.

Figure 3 shows the pipe extended.

Figure 4 shows the hose and pipe-coupling.

Like letters of reference indicate corresponding parts in all the figures.

In the drawings, A represents the lower platform, and B the upper; the whole machine setting on wheels a a. The upper platform is firmly held and supported by four stanchions or pillars, b b. More or fewer supports may be used, if desired.

C is the outer case of the pipe, preferably made of metal, the lower end setting into a hollow socket, D, in which it freely turns.

E is the inner metal pipe, having a narrow flange its entire length; which runs in a corresponding groove in the top of the outer case C. This is to keep the pipe from turning in the case, as the pipe and case turn together.

To its upper end, at d, is coupled or securely fastened an elastic pipe, F, having a spiral spring or its equivalent cover, u, which allows the depression of the nozzle e, as shown in red lines. To accomplish this, I attach a light chain or guide-rope, f, near the nozzle, which is operated by firemen below, as, at the height which the pipe is to be elevated, it would be impossible to work it by hand. The spiral-spring cover causes the nozzle to come back at once to the perpendicular, when the strain on the guide-rope f is slackened.

At the lower end of this pipe, and inside the outer case, I attach a coupling, g, by screwing it firmly on the pipe, the outside of the coupling being made annular or bulging, as shown in fig. 4, at h, in order to fill the space between pipe E and outer case C, when it is worked up and down. The lower end of the cou-

pling is made with a thread, to which is screwed sufficient length of hose, K, to pass through the entire length of outer case C.

To elevate this hose and extend the inner pipe, I attach to the outside edge of the coupling g, as shown at x, in any suitable manner, the end of a belt, v, made of chain, metal, rubber, or other material, which I carry up between the inner pipe and outer case to the top of the latter, where is firmly fastened a frame, i, holding two rollers, j and k, one above the other. I then pass the belt over the top of the upper, and between it and the lower roller; it is then carried down and fastened to the drum of a wheel, l, which is actuated by crank m, and as it works around, the inner pipe is raised up. The drum has an outside ratchet-wheel to hold it as the pipe is gradually raised or lowered, the whole working in a partly-enclosed box, n, attached to the outer case C, at a suitable height from the upper platform, to allow of its being properly worked by firemen when the pipe is elevated.

The pipe and enclosing-case, when not in use, lie lengthwise on the top of the upper platform B, projecting a short distance beyond each end, and resting on suitable supports to steady it. Near the rear end of the upper platform B, the case rests loosely in a swivel, G, which allows the pipe to be raised and lowered.

The platforms A, B have suitable openings at their rear ends, (at o and p respectively,) in which the pipe sets when resting perpendicularly; the position shown in red lines. I attach to the carriage-stanchions, or upper platform, by pivots, a couple of metal guys or stays, r s, which are connected, by their lower ends, to socket D, which hold the case and pipe securely and steadily, as they rest either horizontally or perpendicularly. The rear end of platform A has also suitable recesses, w y, cut in it to admit these guys when the pipe is erect.

In order to raise the pipe to the perpendicular, I attach to the socket D a rope or chain H, which passes down under the carriage and over a roller, up through the bottom of the lower platform A, where it is attached to a small windlass, I, fastened to the platform. By turning the windlass, the rope or chain winds around and pulls the lower end of the pipe towards the ground, while the upper end is raised. As it rises, the pipe gradually slips through swivel G, the guys moving downward, and, at the same time, holding and keeping the pipe steady. A ratchet or stop is attached to this windlass, to prevent its slipping while the pipe is being raised, and holds it when in an upright position. To hold the pipe more firmly, however, I intend to employ, if found necessary, a number of stays, either of rope, wood, or iron, to be attached in any-suitable manner to pipe E and case C. A holding-ring, L, having eyes, z z, is passed around case c for this purpose.

To keep the machine from vibrating by the force of water passing through the hose and pipe, I make the

hind axles hollow from the wheel-hub, N, inward a suitable distance, and pass into these holes bars J, with supports attached to their outer ends, which act as a wagon-jack, giving the machine, by this method, a more lateral brace, and raising the hind wheels, to prevent them from turning.

To further aid in steadyng the machine, I attach to the lower platform A, a reservoir, M, which can be instantly filled with water, thus giving the additional weight necessary, without having to carry it about.

I place a railing, *t t*, around the back of the platform B, to prevent persons working the pipes from falling off.

By making the outer case *c* at least thirty feet, for example, would give, by extending the inner pipe E, sixty feet, which, added to the length of flexible pipe F, say five feet, would give an entire extension of from sixty-two to sixty-five feet over all. This case and pipe, however, can be made as long as desired.

My machine, among other advantages, obviates the slow, dangerous, and laborious task now in vogue of carrying hose up long ladders, which, before it can be accomplished, allows great headway and ruinous progress to fires. My apparatus is always ready for use, it takes but few men to work it, its arrangements are simple, and not liable to get out of order, and it is quickly moved from place to place, either by hand or horse-power.

The pipe can be raised instantly, ready for the water, and turned in any position. It will prove of incalculable value in cases of fire in churches, public build-

ings, or high houses. A large proportion of fires appear to originate in the roofs or upper parts of buildings, and much valuable property and many fine buildings would have been saved had such a machine as mine been in existence, and which I have made to meet just such emergencies. One of its chief advantages is, that it takes a large body of water up to a desired height, and then ejects it from the pipe on the fire in a continuous stream, instead of being scattered in spray, as is the case with fire-hose as now operated.

If found more feasible, I propose to elevate the hose by similar devices within described, but doing away with case C, and raising the hose on its outside, or equivalent.

What I claim as my invention, and desire to secure by Letters Patent, is—

1. The reservoir M, swivel G, windlass I, and the extension-pipe C E, in combination with the platforms A and B, as and for the purpose described.

2. Pipes E and F, the latter having a spring-cover, *u*, guide-rope *f*, annular coupling *g*, and belt *v*, in combination with case C, socket D, raising and lowering-devices *i j k l n*, and guides *r s*, as herein set forth.

3. The hollow axle N, with bars and supports J, as specified.

In witness whereof, I have hereunto signed my name in the presence of two subscribing witnesses.

LESTER DAY.
